UNITED STATES PATENT OFFICE.

CHARLES POTTER, JR., OF PLAINFIELD, NEW JERSEY.

LITHOGRAPHIC-PRINTING MACHINE.

SPECIFICATION forming part of Letters Patent No. 317,194, dated May 5, 1885.

Application filed July 1, 1884. (No model.)

To all whom it may concern:

Be it known that I, CHARLES POTTER, Jr., of Plainfield, in the county of Union and State of New Jersey, have invented an Improvement in Lithographic-Printing Machines, of which the following is a specification.

In printing-presses adapted to printing from a lithographic stone or zincographic plate water is used for moistening the surface, and a vibrating roller has been provided between the rollers in the water-trough and the rollers that supply the water to the printing-surface. This vibrating roller is usually of felt or other absorbent material, and the quantity of water supplied to the printing-surface depends upon the length of time the felt roller is in contact with the roller that revolves in the water-trough. In presses heretofore built the vibrating roller has been placed upon arms connected with a cross-shaft, and upon this shaft there has been a slotted lever with an adjustable roller, and upon the bed of the press a wedge having a horizontal portion to run over the adjustable roller and according to the horizontal adjustment of the roller, so the same was acted upon sooner or later in the reciprocation of the bed by the wedge to bring the vibrating transfer-roller into contact with the water-roller and hold the same for a greater or less length of time. In the adjustment of the roller it is brought nearer to or farther from the fulcrum of the lever, and the extent of motion given to the vibrator is not uniform, and it presses hardest against the water-roller when it remains the longest in contact therewith. In cases where the adjustment has been made at an intermediate lever, the whole lever and fulcrum have had to be moved.

My invention is made for overcoming this last-named difficulty, and for adjusting the time of contact of the vibrating roller with the water-roller without stopping the press, and without varying the amount of motion given to the vibrating roller. I also provide means for adjusting the position of the vibrating roller with accuracy.

In the drawings, Figure 1 is a side view of my apparatus with the frame removed; and Fig. 2 is an elevation with the frame in section, and with parts broken away.

The reciprocating bed A is adapted to receive the stone or other printing-surface. The wetting-rollers B C, intermediate roller, B', water-trough D, water-roller E, and vibrating roller F are of any known or desired character.

The jaws g, at the ends of arms upon the cross-shafts h, serve to hold and move the vibrating roller F.

The wedge k, upon the bed A, and the roller l are similar to those before used; but instead of the axis of the roller l being held in a slotted lever extending out from the shaft h, I place the said axis in the horizontal slot i of the cross m. This slotted cross m is united at its upper end by a joint to the lever-arm o, that extends from the shaft h. I prefer to introduce a connecting-link, p, pivoted at one end to the lever o and at the other end to the slotted cross m; and an adjusting-screw, v, holds the link p firmly to the lever o, but allows of adjusting the parts to regulate the position of the vibrating roller in its relation to the slotted cross.

The axis of the roller l is upon a block that can be moved along in the slot i of the cross m and held. I prefer to use the screw r, passing through this block like the screw in a slide-rest, so that the block and roller can be adjusted while the press is running, and they will be securely held.

The slotted cross is guided at its lower end preferably by a pin, t, in a slot, and a spring, u, acts to lift the cross and move the lever and vibrating roller, so that the latter remains in contact with the intermediate roller, B', above the wetting-rollers C D, except when the wedge k on the press runs over and depresses the roller l and moves the vibrating roller F into contact with the water-roller E.

It will now be understood that the slot of the cross being horizontal, and the movement given by the wedge k to the roller l being always the same, the leverage will not be varied by the adjustment of the roller l in the slot of the cross, and hence the motion communicated to the rock-shaft h and vibrating roller F will always be the same, the adjustment of the roller l simply varying in the time during which the vibrating roller is receiving water from the water-trough roller, and hence the

volume of water supplied to the wetting-rollers each impression can be regulated as required.

A pin might take the place of the roller *l* 5 and a rib the place of the slot in the cross, these being known equivalents.

I claim as my invention—

1. The combination, with the water-trough, 10 roller, vibrating roller, arms, and rock-shaft, of a lever-arm connected to the rock-shaft, a slotted cross, a roller, means, substantially as specified, for adjusting and holding the roller, and the wedge upon the bed, substantially as specified.

15 2. The combination, with the slotted cross

and lever-arm, of the link and adjusting-screw *r*, the vibrating roller, and the trough and water-roller, substantially as set forth.

3. The combination, with the wedge on the bed, of the roller, the slotted cross, the adjusting-screw *r*, the lever-arm, rock-shaft, adjusting-link, and vibrating roller, substantially as specified. 20

Signed by me this 10th day of June, A. D. 1884.

CHARLES POTTER, JR.
